UNITED STATES PATENT OFFICE.

CHARLES M. HINE, OF ST. LOUIS, MISSOURI, ASSIGNOR TO JUDSON M. BEMIS
AND STEPHEN A. BEMIS, OF SAME PLACE.

SEWING-MACHINE.

SPECIFICATION forming part of Letters Patent No. 240,414, dated April 19, 1881.

Application filed September 18, 1880. (No model.)

To all whom it may concern:

Be it known that I, CHARLES M. HINE, of St. Louis, Missouri, have made a new and useful Improvement in Sewing-Machines, of which 5 the following is a full, clear, and exact description, reference being had to the annexed drawings, making part of this specification, in which—

Figure 1 is a view in perspective, showing 10 that portion of the sewing-machine with which the improvement is immediately connected; and Figs. 2 to 9, inclusive, views of the hook, showing it as it appears at various points in its rotation, Figs. 2, 4, 6, 8 being in front elevation, and Figs. 3, 5, 7, 9 being in side elevation.

The same letters denote the same parts.

The present invention is an improvement in single-thread sewing-machines, such as the 20 Willcox & Gibbs machine, and it relates especially to the hook that takes the thread from the needle.

To provide an inexpensive hook, readily made of wire or like material, without any corners or 25 notches wherein the thread can catch or wear the hook, and one by means of which the thread can, by the continuous revolution of the hook, be steadily and properly taken from the needle and cast off, is the aim of this improvement.

Referring to the drawings, A represents the 30 needle of a sewing-machine having the improved hook.

B represents the hook, held in the hook-shaft. C. The hook is made from wire, having the 35 point b, coil b', and shank b², as shown in the

drawings. In Figs. 2 and 3 the hook is taking the thread from the needle. In Figs. 4, 5 the hook has made a quarter-turn. In Figs. 6, 7 it has made a half-turn, and in Figs. 8, 9 a three-quarters turn, and is ready to release 40 the thread. The coil b', in front elevation, is preferably not exactly circular, but is elongated in the direction x x, Fig. 2. The inner part, b³, of the coil b' is shaped as shown mainly to prevent any sharp bends in the hook and to 45 aid in casting off the thread.

I am aware that semi-rotating hooks have been before used; but I claim none of these, as my device is confined to the continuously-revolving hook, which, by its peculiar construction, will, in operation, take the loop of the thread on its point, carry it part way along its coil, and then, in the continued revolution of the hook, by its reverse action on the thread, cast off the loop, the said hook all the while 55 having a direct forward revolution on its axis.

I claim—

The revolving sewing-machine hook B, having the point b, coil b', shank b², and inner part, b³, whereby, in a continuous revolution, 60 the stitch or loop is taken on its end, carried part way along, and then, by the reverse movement of the bent portion of the hook on the thread, is cast off at the proper moment, substantially as shown and described.

C. M. HINE.
